[57] ABSTRACT

A latching mechanism is provided, such mechanism having a slide held in latched position by a cam received in a recess in the slide, the cam in turn being retained in holding position by a release latch. Upon application of a low magnitude force to the release latch, the cam displaces from its holding position into either the slide recess or the space which the release latch vacated upon movement thereof to unlatch the slide and allow it to slidably move to an unlatched position and perform a specified function.

LATCHING MECHANISM

The invention described herein may be manufactured, used and licensed by or for the Government for governmental purposes without the payment to us of any royalties thereon.

BACKGROUND OF THE INVENTION

Various types of releasing devices or latch mechanisms are known which function such that upon application of a force to a component of the mechanism, another component is released or unlatched to perform a specified function. Such a mechanism, for example, can be a latching device in which a slide is held restrained in a latched position by a latching member, so that upon release of the latching member, the slide moves to an unlatched position for performing a specified function. One application involving the use of such types of release or latch mechanisms is in large caliber artillery projectiles wherein they can be employed in various ways, e.g., to arm the projectile following firing. Thus, the movable component or slide might be used to unobstruct a firing course in the projectile which prior to firing was blocked as a safety measure to preclude accidental ignition of the bursting charge.

Such release mechanisms as are known in the art, particularly as employed in artillery projectiles have certain disadvantages. For example, dash-pot devices commonly have been employed in the manner and for the purposes mentioned before. Such dash-pot devices, however, are difficult to maintain and since they utilize hydraulic fluid in their operation, present a problem respecting possible fluid leakage which can prevent proper operation of the dash-pot rendering the projectile unsuited for its intended purpose. Other known forms of release or latch mechanisms are generally complicated in construction, have numerous parts and are expensive to make and assemble and maintain.

The present invention overcomes the shortcomings of prior art release or latch mechanisms, particularly as such mechanisms are known for use in artillery projectiles.

SUMMARY OF THE PRESENT INVENTION

The release mechanism of the present invention is a device which functions responsive to the application of a force of low magnitude to a latching component thereof to release under relatively high energy load, a movable component or slide from a latched position to permit the movable component to perform a specified function.

The release mechanism of the present invention can be used for any one of a number of purposes heretofore provided by latching mechanisms and is particularly suited for use in an artillery projectile for the purpose of arming the projectile following firing of the latter. In one form, the release mechanism includes a housing having a passage therein in which is received a sliding component, such sliding component having an enlarged recess formed therein. The housing also includes a second passage in which is slidably received a release latch, the release latch being employed normally to maintain a movable cam engaged in the recess of the movable component to hold the latter in a latched position in opposition to the biasing force of a spring which functions to slide the component away from its latched position. The release latch is maintained in its cam-holding or latching position by means of a toggle device. Upon application of a low energy force to the release latch which would slide it away from its latching position, the cam is freed to fulcrum against a fulcrumming surface within the housing and is moved out of the recess in the movable component thereby permitting the movable component to slide from its latched position to a second position, during the course of which movement the movable component performs a specified function. In such form of the mechanism, the cam is designed to retract from the recess of the movable component and locate fully within the release latch passage upon unlatching of the mechanism. When used in an artillery projectile, the release or latch mechanism can be operated by using the centrifugal force of the rapidly rotat-

ing projectile as the means for applying a low magnitude force to the release latch to slide it from its latching position. The movable component or slide during the course of its movement from a latched to an unlatched position can be employed to pivot a blocking lever away from blocking position across a passage in a firing tube within the projectile and thus arm the projectile.

5 A modified form of the mechanism provides that the cam upon movement of the release latch, retracts fully into the recess of the movable component.

When used in artillery projectile and for providing proper balance of the projectile during the course of its post-firing flight, the mechanism can be provided pairs of movable components or slides and associated elements arranged symmetrically of the axis of the projectile with control or unlatching of the slides being achieved with a single release latch.

10 The invention accordingly comprises the release or latch mechanism possessing the features, properties and relation of elements which will be exemplified in the devices hereinafter described and the scope of the present invention will be indicated in the claims.

BRIEF DESCRIPTION OF THE DRAWINGS

15 The invention and a fuller understanding of its nature and objects will appear more clearly from the following detailed description taken in conjunction with the accompanying drawings shown by way of example preferred embodiments of the inventive concept and in which:

20 FIG. 1 is a plan view of a release or latch mechanism constructed in accordance with the principles of the present invention, the movable component or slide thereof being shown in latched position, a portion of the housing being broken away to illustrate the structural components therein.

25 FIG. 2 is a plan view similar to FIG. 1 showing the moved or unlatched position of the movable component or slide following unlatching thereof, and the manner in which it functions to pivot a blocking lever away from a firing passage in an artillery projectile to arm the latter.

30 FIG. 3 is a sectional view depicting a modification of the device shown in FIGS. 1 and 2 as it is embodied in an artillery projectile wherein for purposes of balance, the device is provided with movable components and cams arranged symmetrically at each side of the projectile axis.

35 FIG. 4 shows the unlatched condition of the mechanism depicted in FIG. 3.

40 FIG. 5 is a plan view of a release mechanism similar to that shown in FIGS. 1 and 2 but modified to the extent that upon unlatching, the cam moves into the recess in the movable component or slide and is carried along therewith during its travel from latched to unlatched position, the slide being shown in latched position.

45 FIG. 6 is the same as FIG. 5 except it shows the slide in unlatched position.

50 Throughout the following description, like reference numerals are used to denote like parts in the drawings.

DESCRIPTION OF THE PREFERRED EMBODIMENTS

55 The release or latch mechanism of the present invention can be made in various embodiments as will be described later, it being understood however that the same latching-unlatching principles are used in the various forms of the mechanism. In the following description, the use of expressions such as "top," "bottom," "left side," "right side," etc. are employed as terms of convenience in describing the various elements of the mechanism. They should not be understood as implying any limitation as to the physical positioning of the mechanism in use.

60 Referring now to form of mechanism 10 depicted in FIGS. 1 and 2, it includes an elongated housing comprised of a cover plate 12 superposed on and coextensive with a casting 14, the lower or bottom side of the casting being provided with a removable stop plate 16, the stop plate 16 and cover plate 12

being fastened to the casting 14 by means of machine screws 17. The casting 14 is provided with a number of specially-shaped segments including a segment 18 at the left end and extending from top to bottom of the housing, a segment 20 at the other or right end at the bottom of the housing adjacent the plate 16 and a segment 22 at the top of the housing or the side thereof remote from the stop plate, such segments being arranged as will appear to define and provide within the housing certain passages and cavities. Thus, the segments 18 and 20 are provided with flat parallel spaced edge faces 24, 26 respectively, which are arranged such as to define a first passage 28 disposed transversely of the housing and in which can be received for sliding travel therein, an elongated slide 30. Slide 30 is provided with a relatively deep recess 32 extending laterally inwardly from a side thereof as shown in which can be received one end of a cam 34 received loosely in the housing, the recess 32 having a flat bottom 301 disposed perpendicular to the faces of the slide. Similarly, segments 20 and 22 are provided with parallel arranged straight edges 37 and 38 respectively arranged such as to define a second passage 40 in the casting in which can be slidably received a release latch 42, the passage 40 being disposed in the casting so as at a left end section thereof of reduced dimension to intersect and communicate with the passage 28, the arrangement being such as passage 40 is disposed longitudinally of the housing and substantially perpendicular to passage 28. As will be noted in FIG. 1, the recess 32 in the slide with the latter in the latched position, registers with passage 40.

Segment 20 of the casting is provided with an enlarged open portion or cavity 49 wherein is received for pivoting movement therein, a toggle assembly 46, the toggle assembly being employed to apply a certain biasing to the release latch to normally maintain the latch 42 in either a latching or non-latching position as shown in FIGS. 1 and 2 respectively. The toggle assembly 46 includes complementary longitudinally arranged, slidably longitudinally overlappingly engaged pin elements 48 and 50, the respective pin elements being provided with flanges 52 between which extends a compression spring 54 and the assembly of its opposite ends being engaged with segment 20 and release latch 42 respectively. The spring 54 tends to slide the pin elements 48 and 50 axially in opposite directions thereby maintaining the opposite rounded ends of the toggle assembly in firm engagement with the rounded recesses 56 and 58 in the casting segment 20 and release latch 42 respectively.

Slide 30 which is coextensive with and fully retracted in passage 28 when in a latched position (FIG. 1) is provided with a blind bore 31 in which is received a compression spring 33, the compression spring engaging against the inner surface of stop plate 16 and acting to urge the slide upwardly away from the stop plate and outwardly of the housing. With the mechanism in latched condition, one end, i.e., the left end of cam 34 in its held position is received in the recess 32 of the slide, the cam having one straight longitudinal side edge 62 in abutment with complementary straight portion 301 of recess 32. The other end of the cam straight side edge 62 is supported on the flat upper surface 72 of a tongue extension 70 formed at the left end of the release latch 42. The other longitudinal side edge 64 of cam 34 also is rounded taperingly toward side edge 62 in the direction of the left end and serves to facilitate retraction of the cam from the slide recess as will be described later. One side of the slide recess 32 is rounded adjacent its entrance as at 35 so that such rounded portion functions engage the straight side edge of cam 34 with unlatching of slide 30 to initiate ejection of the cam 34 from the recess 32 by fulcruming it against the fulcruming surface to be described next. Casting segment 20 is provided with a convexly rounded surface 60, which surface curves outwardly relatively of the entrance of the recess 32 in the slide 30 so that such surface provides a fulcruming surface against which the cam 34 can pivot as well as clearance to enable cam 34 to retract from recess 32 and outwardly therefrom into passage 40 during unlatching of the mechanism.

When the mechanism is in latched condition, slide 30 is fully retracted within the housing 10 as shown in FIG. 1. The slide is held in that condition by reason of the engagement of the cam 34 at one end in recess 32 in the manner depicted in FIG. 1, the cam in turn being held in retaining position by release latch 42 and more particularly the engagement of flat surface 72 of release latch extension 70 with the right or other end of the cam 34. The release latch 42 in turn is held in its latching position by means of toggle assembly 46 which exerts a biasing force against the release latch to hold it in the extreme left-hand position shown in FIG. 1. When a pulling force of relatively small magnitude is applied to release latch 42 so as to slide it from left to right, such force, e.g., centrifugal force if the mechanism is embodied in a rapidly spinning body such as projectile, will slide the release latch to the right and the toggle assembly will pivot clockwise about groove 56. When the pulling force has displaced the release latch 42 a sufficient distance to bring the toggle assembly past its point of no return, the toggle assembly will now function to bias the release latch completely to the right hand position shown in FIG. 2. At about the time the toggle assembly has reached its point of no return, the extension part 70 of the release latch will move out from under the right hand end of cam 34 freeing the cam from the restraint which held it in static position. The cam now being free to move, starts to pivot in a clockwise direction under the impetus of the upwardly moving slide 30 under the influence of compression spring 33. As soon as the slide starts to move upwardly, the rounded recess edge 35 will engage the straight edge lower surface 62 of the cam to effect fulcruming of the cam against rounded surface 60. Continued upward travel of slide 30 exerts a force against the cam to displace the latter rightwardly completely out of the recess 32 and with sufficient magnitude to displace the cam into passage 40, the rounded other longitudinal side edge 64 of the cam slidably abutting with segment edge 38 during such movement. With the cam freed from the slide recess 32, the slide will continue its sliding travel to its second or unlatched position shown in FIG. 2.

The latching mechanism 10 depicted in FIGS. 1 and 2 can be used for various purposes wherein upon moving from a latched to unlatched position, a slide is intended to form a specified function. One such function could be the arming of a projectile following firing of same. As shown in FIG. 2 such arming could involve pivoting a blocking lever 200 out of blocking position in front of a firing passage 204 in the projectile body 202. With the mechanism in latched condition before firing of the projectile, the blocking lever 200 will occupy the position shown in short and long dashed lines in FIG. 2, and for that purpose suitable spring means or other biasing means (not shown) could be employed to maintain the lever in blocking position. Following firing, centrifugal force acting on the rapidly rotating projectile can be utilized to apply a force F_1 of small magnitude on release latch 42 to slide it from left to right and to thereby release the cam 34 from the slide 30. When the slide moves from its latched to unlatched position as shown in FIG. 2, such movement can be employed to pivot the blocking lever 200 to the position shown in solid lines to uncover the firing passage 204 and thereby arm the projectile.

The latch mechanism of the present invention, as mentioned, can be employed in an artillery projectile. For such use however it is desirable that the mechanism be compatible with maintenance of stability of the projectile during its flight following firing and particularly with respect to distributing the weight of the mechanism symmetrically about the axis of the projectile. For this purpose the mechanism 80 depicted in FIGS. 3 and 4 is provided, the construction being such that a pair of slides 81, 81a are used and are disposed symmetrically one at each side of the projectile longitudinal axis X-X. The mechanism is contained within a housing 89, and includes cams 83, 83a associated with the respective slides 81, 81a and being received in recesses 82, 82a formed in the slides in the same manner as described earlier. The slides are retained in latched condition by the cams and a latching piston 84, the

piston having a section of reduced diameter 85 at the face end thereof which engage the cams when the piston is in full left-hand latching position. The piston is maintained in latching position by means of a stopper or release pin 90 maintained in the left-hand position shown in FIG. 3 and connected with a flange 91 fixed on piston rod 87. A spring 86 in compressed position encircles the piston rod and acts to hold the piston 84 in its latching position. On release of release pin 90, piston rod 87 will be moved rightwardly by the action of compression spring 86 until flange 91 abuts surface 93, at which point spring 86 retains just sufficient compression to hold piston 84 in its latching position. Upon impact, a force of inertia F_2 causes latching piston 84 to compress spring 86 and to move from left to right from the position shown in FIG. 3 to that shown in FIG. 4. Thereby the restraint against movement of cams 83, 83a applied by piston 84 is released and slides 81, 81a become unlatched and slide outwardly of the housing 89 to perform a specified function. The movement of the slides 81, 81a when they are unlatched is provided by springs (not shown) in the same manner as described earlier in connection with mechanism 10.

The latch mechanism 110 shown in FIGS. 5 and 6 is modified somewhat from that shown in FIGS. 1 and 2 with respect to the plan profile shape of the cam 134 and the construction of the segments 122 and 120 as compared with the corresponding segments used in the mechanism 10. Moreover, the latch mechanism 110 functions such that upon unlatching of the slide 130, the cam 134 retracts into the recess 132 of the slide to clear it from its latching position whereas in the latch mechanism 10, the cam is received in the latching lever passage. On the other hand, the construction of the mechanism 110 in all other respects is substantially identical with that of the mechanism 10. Thus, the latch mechanism 110 includes a housing having a cover plate 112 coextensive with and covering one face of a shaped casting 114, a stop plate 116 and machine screws 117 holding the cover plate and stop plate fixed to the casting. Further, the casting includes segments 118, 120 and 122 which are formed with the respective edges 124, 126, 137 and 138 to define the passages 128 and 140 in which are received the slide 130 and release latch 142. The mechanism 110 also includes a toggle assembly 146 provided with the same components and functioning in the same manner as the toggle assembly of mechanism 10 except that the toggle assembly 146 is anchored in the upper segment 122 being received in rounded groove 156 therein and engages with an upper edge of the release latch 142 in groove 158. Furthermore, the tongue extension 170 of the release latch 142 is provided with a flat tongue surface 172 like that on release latch 42 of mechanism 10. The mechanism 110 also is provided with a compression spring 133 received in the blind bore 131 of the slide 130 for the purpose of moving the slide following unlatching thereof.

The cam 134 of mechanism 110 as will be noted is different in its profile or plan shape than the cam 34 and has a relatively wide portion at one end including a convexly rounded end edge 165 formed complementary with the curved portion 167 of recess 132 in slide 130. The cam has a straight longitudinal side edge 162, which at the other, narrow end 180 of the cam rests against the surface 172 of the tongue extension 170 of release latch 142. The recess 132 formed in the slide 130 is enlarged but similarly shaped with respect to the cam profile so as to adapt it to receive the cam as the latter retracts during unlatching of the mechanism. Segment 122 of casting 114 is provided at the corner thereof adjacent the intersection of passage 140 with passage 128 with a rounded fulcruming edge surface 135, and the other longitudinal side edge of the cam is provided with a complementary concavely rounded section 235 which abuts with rounded edge 135 during fulcruming of the cam.

In operation, the mechanism 110 functions like mechanism 10 in that release of the latching lever by a force F_3 of low magnitude, will slide the tongue extension 170 on the release latch from beneath the edge 162 of the cam at its narrow end

180, allowing the rounded surface section 235 of the longitudinal edge 164 of the cam to abut with and fulcrum against fulcruming surface 135 so that upward travel of the unlatched slide will rotate the cam clockwise moving it into the recess 132 in the slide and completely retracting it from the release latch passage 140 to allow for unimpeded movement of the slide to its fully unlatched position. The various positions the cam 134 has following release of it from its holding position and during the movement of the slide 130 from retracted to unlatched position in the housing are shown in phantom lines in FIG. 6. Thus, it will be noted that as soon as the cam is released from its held position it starts to pivot clockwise and the rounded surface 165 at the left end of the cam rolls against the concave surface 167 of recess 132 until the slide reaches about mid length in its travel from latched to unlatched position, at which point the pivoting of the cam moves it against the side edge 126 of the passage 128. In the latter condition, the cam is completely retracted within the recess 132.

It will be understood that in accordance with the present invention various modifications can be made in the construction of the latch mechanism. For example, the housing need not comprise a casting 14. Rather, the segments 18, 20, 22 could be provided as separate items and assembled to a plate similar to the cover plate 12. Furthermore, the biasing means employed to bias the release latch into latching position could be a type other than a toggle assembly. Other forms of biasing means could be employed.

It will thus be seen that the objects set forth above, among those made apparent from the preceding description, are efficiently attained and, since certain changes may be made in the above construction without departing from the scope of the invention, it is intended that all matter contained in the above description or shown in the accompanying drawings shall be interpreted as illustrative and not in a limiting sense.

What is claimed is:

1. Latch mechanism comprising a housing having first and second passages therein, said second passage intersecting said first passage to provide communication therewith, an elongated slide member received in said first passage for sliding straight line travel therein, said slide member having a latched position in said first passage, first biasing means engaging said slide member and tending to slide it in said first passage from said latched position, an elongated release latch received in said second passage for straight line sliding travel therein, said slide member having a recess extending laterally inwardly therein from a side thereof, said recess registering with said second passage when said slide member is in said latched position, an elongated cam, one end of said cam being receivable in said recess, the other end of said cam extending into said second passage, said latch release having a tongue extension at one end thereof, said tongue extension engaging the other end of said cam when said release latch is in latching position for holding said cam engaged in said recess and thereby prevent movement of said slide, and second biasing means normally tending to slide said release latch in one direction in said second passage and into its latching position, a portion of said second passage adjacent its intersection with said first passage being defined by a rounded fulcruming surface juxtaposed with at least a portion of said cam when it is in its held position, sliding movement of said release latch in an opposite direction releasing said cam from its held position whereby unlatching of said slide member is initiated, the movement of said slide member from its latched position effecting fulcruming of said cam against said rounded fulcruming surface for retracting said cam into one of said slide recess and said second passage.
2. The latch mechanism set forth in claim 1 wherein said housing comprises a plurality of shaped segments, each of said segments having at least one side edge surface, said segments

being arranged such that one side edge surface of one segment lies opposed to and defines with a side edge surface of another segment one of said first and second passages.

3. The latch mechanism set forth in claim 2 wherein said second passage extends fully transversely of said housing, said slide in its latched position being coextensive with said passage, said slide moving out of said housing during movement from its latched position.

4. The latch mechanism set forth in claim 3 wherein housing is an elongated structure, said shaped segments being arranged such that said first passage is disposed transversely in said housing and said second passage longitudinally in said housing.

5. The latch mechanism set forth in claim 2 wherein said second biasing means comprises a toggle assembly received in one of said segments for pivoting movement in a cavity formed in said one segment, said toggle assembly including a pair of longitudinally overlapping pins, and spring means engaging said pins to urge them in opposite directions, the assembly at one end being pivoted in said cavity, the other end of said assembly engaging said release latch.

6. The latch mechanism set forth in claim 1 wherein said first biasing means comprises a compression spring engaged at one end with said slide and at its other end with said housing.

7. The latch mechanism set forth in claim 6 wherein said slide has a blind bore extending longitudinally therein from one end of said slide, said compression spring being received in said blind bore, said housing further having a stop plate disposed across one end of said first passage, said compression spring engaging said stop plate.

8. The latch mechanism set forth in claim 1 wherein said cam has at least one straight longitudinal side edge, the tongue

extension of said release latch having a flat surface, said other end of said cam being supported on said flat surface when said cam is held by said release latch in its latching position.

9. The latch mechanism set forth in claim 8 wherein the recess in said slide has a straight section therein, the flat side edge of said cam at said one end being in abutment with said recess straight section when said cam is in held position.

10. The latch mechanism set forth in claim 9 wherein said rounded fulcruming surface is juxtaposed with said one flat

10 longitudinal side edge of said cam, said flat side edge abutting with said fulcruming surface during fulcruming of said cam, said cam retracting into said second passage during movement of said slide from its latched position, the other side edge of said cam being rounded taperingly toward said flat side edge 15 in the direction of said one end of said cam to facilitate movement of said cam out of said slide recess and into said second passage.

11. The latch mechanism set forth in claim 8 wherein the recess in said slide has a concavely curved section therein, said 20 cam having a convexly curved edge at said one end thereof, said convexly curved edge being in abutment with said recess concavely curved section when said cam is in held position.

12. The latch mechanism set forth in claim 11 wherein said rounded fulcruming surface is juxtaposed with the other lon-

25 gitudinal side edge of said cam, said other longitudinal cam side edge having a complementally rounded portion therein, said rounded cam side edge abutting with said fulcruming surface during fulcruming of said cam, the recess in said slide being similarly shaped in plan profile with the plan profile of 30 said cam, said cam retracting into said slide recess during movement of said slide from its latched position.
